Primary Examiner — Richard Kearney*Assistant Examiner* — Michael Hoffman(74) *Attorney, Agent, or Firm* — Casimir Jones, S.C.; Brian F. Bradley(57) **CLAIM**

The ornamental design for a fluid delivery system, as shown and described.

DESCRIPTION

FIG. 1 is a perspective view showing our new design of a fluid delivery system;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in the drawings illustrate environmental subject matter and form no part of the claimed design.

1 Claim, 5 Drawing Sheets# US D1,029,235 S
